(57) **CLAIM**

The ornamental design for an oral therapy device, as shown and described.

DESCRIPTION

FIG. 1 is a top, right, front isometric view of an oral therapy device showing our new design;

FIG. 2 is a bottom, left, rear isometric view of the oral therapy device of FIG. 1;

FIG. 3 is a front view of the oral therapy device of FIG. 1; FIG. 4 is a rear view of the oral therapy device of FIG. 1; FIG. 5 is a right side view of the oral therapy device of FIG. 1;

FIG. 6 is a left side view of the oral therapy device of FIG. 1;

FIG. 7 is a top view of the oral therapy device of FIG. 1; and, FIG. 8 is a bottom view of the oral therapy device of FIG. 1.

The broken lines in the drawings show portions of the oral therapy device that form no part of the claimed design.

1 Claim, 4 Drawing Sheets
